Specification of Letters Patent.

Patented Mar. 4, 1919.

Application filed June 7, 1916. Serial No. 102,291.

To all whom it may concern:

Be it known that I, LOUIS A. CASGRAIN, a citizen of the United States, residing at Beverly, in the county of Essex and State 5 of Massachusetts, have invented certain Improvements in Fastening-Inserting Machines, of which the following description, in connection with the accompanying drawings, is a specification, like reference characters 10 on the drawings indicating like parts in the several figures.

This invention relates to machines for inserting fastenings, and more particularly to machines for inserting screw threaded fastenings into the soles of boots and shoes. 15 The invention is herein shown by way of illustration as embodied in a screw threaded fastening inserting machine of the type disclosed in United States Letters Patent No. 20 490,621, granted January 24, 1893, on an application of Louis Goddu.

Fastening inserting machines of the type illustrated in said Letters Patent comprise a wire carrying spindle arranged to rotate 25 continuously at comparatively high speed, and two lateral shafts having connections with the wire carrying spindle by which they are continuously driven, one of said shafts carrying the cams through which the wire 30 feeding, wire severing, and horn releasing mechanisms are operated. For suspending the operation of the wire feeding mechanism to stop the insertion of fastenings, machines of this type are provided with manually operated means arranged to disconnect the wire 35 feeding mechanism from its operating cam.

Considerable difficulty, however, is encountered in operating machines in which the wire feeding mechanism is so controlled due 40 to the liability of an operator initiating the operation of the wire feeding mechanism at such a time in the machine cycle that it will not impart a complete initial feeding movement to the wire feeding mechanism for feeding the wire into position to form the first 45 fastening, and frequently the first fastening is shorter than the length required for the given thickness of stock.

One of the objects of the present invention 50 is to provide improved mechanism for controlling the operation of the wire feeding mechanism, whereby the full length of wire as required for the thickness of work oper-

ated upon will always be fed by the wire feeding mechanism to insert the first fastening in the work. 55

In the illustrated preferred embodiment of the invention, the wire feeding mechanism is rendered operative at such predetermined times only in the cycle of operations 60 of the machine as will cause the next operative movement of its operating cam to impart a full wire feeding stroke according to the thickness of the work being operated upon. Preferably, too, and as shown, the wire 65 feeding mechanism is controlled through mechanism controlling the wire severing and horn releasing mechanisms and, since these mechanisms are interdependent, the proper sequence of operations essential to 70 the efficiency of the machine is insured.

A further disadvantage resulting from the construction of machines of this type as heretofore designed is that the wire severing and horn releasing mechanisms are 75 maintained continuously in operation even when the machine is not operating to insert fastenings. This causes unnecessary wear of the parts and vibration of the machine. Also, the wire severing cutters become 80 dulled by striking together when they are not operating to sever wire.

With this in view, the present invention aims also to provide improved mechanism for controlling the wire severing and horn 85 releasing mechanisms, whereby the operation of said mechanisms is suspended when the machine is not operating to insert fastenings.

In accordance with this object, the preferred embodiment of the invention comprises a novel controlling mechanism constructed and arranged to render the wire severing and horn releasing mechanisms operative upon the initiation of fastening inserting operations and to disconnect said mechanisms from their operating shaft when the insertion of fastenings is suspended, the controlling mechanism operating also, as above stated, to control the wire 100 feeding mechanism in timed relation to the other mechanisms. 90

As herein shown, the controlling mechanism is so arranged that, regardless of when it is actuated, it operates to suspend the operation of the said mechanisms at such pre- 105

determined times only in the cycle of operations of the machine as will insure invariably complete performance of the functions of these mechanisms, whereby the completion of every fastening inserting operation is insured.

In accordance with a further feature of the invention, there is provided a novel arrangement of the controlling mechanism for the wire severing, horn releasing, and fastening inserting mechanisms relative to the support for the work of a character to insure the maintenance of the work support in operative position until the completion of the final fastening inserting operation.

Other objects and features of the invention will be apparent when the following description is read, in connection with the accompanying drawings and the novel features of the invention are set forth in the appended claims.

Referring to the drawings,—

Figure 1 is a side elevation of a machine for inserting screw threaded wire having embodied therein a preferred form of the present invention;

Fig. 2 is a rear end elevation of the head of the machine;

Fig. 3 is a plan view of the rear end portion of the head;

Fig. 4 is a detail in perspective of a portion of the wire feeding mechanism;

Fig. 5 is a sectional detail of the wire feeding mechanism;

Fig. 6 is a vertical section through the clutch; and

Fig. 7 is a section on the line 7—7 of Fig. 2.

The machine in which a preferred form of the invention is shown as embodied is substantially like that disclosed in the Letters Patent above mentioned except as herein fully described in detail and to this patent reference may be had for a more detailed description of parts herein illustrated but not fully described.

The illustrated machine is adapted to insert screw threaded wire into work supported on a horn 2, the wire being carried by a reel 4 mounted upon the upper end of a vertically disposed wire carrying spindle 6 mounted for rotation in bearings in the machine frame. The spindle 6 is continuously rotated at comparatively high speed by a belt 8 passing over a pulley 10 on the spindle and over an idler 12 to a driving pulley 14 in the base of the machine, the driving pulley 14 being arranged to be clutched to a power driven pulley 16 by a clutch operated through a wedge 18 connected to an operating treadle 20 in the base of the machine. The wire carrying spindle 6 is provided with a worm (not shown) which meshes with worm gears 22 on the forward ends of two horizontal lat-

eral shafts 24 and 26, respectively, which are disposed on either side of the spindle 6 and have other gears 28 and 30, respectively, on their rear ends to compensate for the rearward thrust of the shafts caused by the worm and gear connection with the spindle 6. The shaft 26 carries the various cams by which the feeding and severing of the wire and the feeding of the work are effected and by which the release of the horn 2 to permit feeding of the work is controlled. The various operating cams are preferably formed so as to cause two operations of the several mechanisms during a single rotation of the cam shaft.

The wire feeding mechanism comprises a wire feed lever 34 (Fig. 4), pivoted at 36 on the frame and having two forwardly extending arms 38, the outer end of each arm 38 being provided with a segmental gear 39 which engages a co-operating rack on a yoke 40 formed on a sleeve which is slidably and rotatably mounted on the spindle 6. The lever 34 has an upwardly extending arm 42 carrying a cam roll 44 which is adapted to be engaged by an edge face 45 on the wire feeding cam 46 to oscillate the feed lever 34 and, through the rack and gear connections with the sleeve, cause it to move downwardly to insert the wire into the stock, the lower end of the sleeve being provided with wire gripping devices 48 which grip the wire and draw it from the reel upon the downward movement of the sleeve. Yielding means (not shown) substantially of the construction illustrated in the above-mentioned Letters Patent are provided to keep the cam roll 44 normally in engagement with the edge face 45 of the cam 46.

The operation of the wire severing cutters 65 to sever the wire after a proper length of wire has been inserted in the work is effected by a cam 62 carried by the shaft 26. This cam is provided with tappets 63 adapted to engage one end of a lever (not shown) the other end of which lever is arranged to oscillate a horizontal shaft on the outer end of which means for operating the wire cutters 65 is mounted, the construction and operation of the cutters being more fully shown and described in said above mentioned patent. The feeding of the work between each two fastening inserting operations is effected by a feed wheel 60 operated from a cam groove 52 formed in the side of the cam 46 and connected through levers 54 and 56 and a horizontal shaft 58 to the feed wheel 60.

The horn 2 for supporting the work is maintained normally in position to clamp the work against an abutment 3 during the fastening inserting operation by a comparatively strong spring 66. To permit the work to be fed between successive inserting

operations, the horn 2 is periodically depressed against the tension of the spring 66 by horn releasing mechanism comprising a lever 68 provided with a cam roll which engages a cam groove 70 in the side of the wire severing cam 62 and having a link connection 72 to a pawl carrying slide 74 forming part of an automatic horn release and work thickness compensating means 5 which is substantially like that shown and described in United States Letters Patent No. 383,455, granted May 29, 1888, on an application of Louis Goddu. The cooperating slide 76 of the horn releasing means is 10 connected by a rod 78 and toggle 80, 82 to one end of a lever 84 fulcrumed at 86 in the base, the other end of the lever being connected by a rod 88 to the horn supporting shaft 90, the toggle 80, 82 being provided in 15 order to enable the horn to be finally depressed to a greater extent than is effected by the automatic horn releasing means. The link 82 of this toggle has a pivotal connection with the end of a link 92, the pivotal 20 stud 94 being received in slots in a casing attached to the rod 78. The forward end of the link 92 is provided with a slot which receives a stud 93 on a tail piece 96 on a lever 98 pivoted at 100 in the base of the machine. The slot in the link 92 permits lost motion when the treadle 98 is released to prevent a premature lowering of the horn before the fastening is completely inserted. 25

In accordance with the present invention, 30 the wire severing and horn releasing mechanisms are normally maintained inoperative when the machine is not operating to insert fastenings, thereby eliminating unnecessary vibration of the machine and reducing the wear of the parts. Also, said mechanisms are rendered operative at predetermined times when it is desired to insert fastenings. 35

The illustrated means for controlling the operation of these mechanisms comprises a 40 clutch mechanism constructed and arranged to connect the wire severing and horn releasing cam 62 with its actuating shaft 26 automatically at such times as will insure a complete operation of the wire severing and horn releasing mechanisms and to disconnect the cam 62 from its operating shaft at predetermined times only when the insertion of the fastenings is suspended. This clutch mechanism comprises a sleeve 102 (Fig. 6) 45 rigidly secured by a pin 104 to the rear end of the shaft 26 and having secured thereto by bolts 106 the gear 30 which meshes with the gear 28 on the shaft 24. 50

The sleeve 102 is provided with two longitudinally extending recesses 108 and 110 located on opposite sides of the sleeve and adapted to receive plungers 109 and 111, respectively, which are normally pressed outwardly by springs 112 and 114, respectively. The outer ends of the plungers 109 55

and 111 are enlarged and are adapted to be received in two sockets 116 and 118 provided in the rear face of the wire severing cam 62 when the cam occupies a position in which the sockets and the plungers are in alignment, that is, directly after the cam has effected an operation of the wire severing cutters. The rear ends of the plungers 109 and 111 project through the rear end of the sleeve 102 and are secured to a collar 120 60

slidably mounted upon the sleeve 102 and having a peripheral groove 122. The plungers are normally held withdrawn from the sockets 116 and 118 in the cam 62 by a yoke member 124 (Figs. 2 and 3) which is pivotally mounted upon a vertically disposed shaft 126 and has two arms 128 and 130, the upper arm 128 extending above and at right angles to the shaft 26 and the lower arm 130 extending parallel to the arm 128 and 65 below the shaft 26. Intermediate between the ends of the arms 128 and 130 are rolls 132 and 134 mounted on studs 136 and 138 carried respectively on the arms 128, 130, these rolls being arranged to travel in the 70 groove 122 in the collar 120. The arms 128 and 130 intersect at their outer ends and carry a hardened steel plate 140 having a beveled surface 142 which engages a similarly beveled surface on the end of a lever 75 or latch 144 pivoted at 146 on the machine frame. A spring pressed plunger 148 located in a recess in a lug on the frame has its outer end engaging an offset portion of the lever 144 to maintain the lever normally 80 in engagement with the outer end of the yoke 124. An arm 150 pivoted on a stud 152 on the end of the said yoke carries at its forward end a cam roll 154 and at its rear end is loosely connected to the forward 85 end of a rod 156 by an integral collar 158. This end of the rod 156 carries an adjustable spring casing 160 which receives a spring 162 bearing against the collar 158 of the arm 150 and tending to maintain the 90 said arm against an adjustable stop 164 on the rod 156. The opposite end of the rod 156 is pivotally connected by a stud 166 to one arm 168 of a bell-crank lever rigidly mounted on a horizontally extending shaft 110

170. The forward end of this shaft carries an arm 172 fast thereon and having its outer end connected by a treadle rod 174 to the rearwardly projecting arm 176 of the treadle 98. A pull spring 178 secured at one end 115 to the frame and at its other end to a collar on the rod 174 acts normally to maintain the clutch mechanism inoperative or in the position illustrated in Fig. 3, in which position the end of the lever 144 is in engagement with the end of the yoke 124 thereby holding the plungers 109 and 111 out of the 120 cooperating sockets in the cam 62. Depression of the treadle 98 causes the arm 150 to be turned about its pivot 152 into position 125 130

for the cam roll 154 carried on the forward end of the arm to engage a beveled face 179 on the lever 144 and move the outer end of the lever out of engagement with the end of the yoke 124 to release it whereupon the springs 112, 114 of the clutch mechanism immediately move the plungers 109, 111 into clutching or operative relation to the wire severing cam 62.

10 In order that the cam 62 may be positively and automatically disconnected from its operating shaft 26 at a predetermined point in the cycle of operations of the machine, a face cam 180 is adjustably secured to the 15 rear face of the gear wheel 28 fast on the shaft 24 by bolts 181 which project through slots 183. The acting edge face 182 of this cam is adapted to engage the cam roll 154 on the arm 150 when said arm is in the position it assumes upon the release of the treadle 98. The acting edge face 182 is so formed that when it engages the cam roll 154 of the lever 150, it first rocks the lever about its pivot into position to compress the spring 25 162, or to the right, Fig. 3, and then moves the lever longitudinally which causes the outer end of the yoke 124 to be moved rearwardly and the plungers to be withdrawn from the sockets 116 and 118 in the wire severing and horn releasing cam 62. After the cam 180 has imparted its full throw to the lever 150 which moves the yoke 124 into position to be engaged by the arm 144 and held in inoperative position the compressed 30 spring 162 immediately acts upon the rear end of the lever 150 to move its forward end to the left, Fig. 3, clear of engagement with the cam 180. The cam 180 is so timed with relation to the other parts of the machine 35 that the cam 62 is always disconnected from the shaft 26 immediately after the length of wire just inserted into the stock has been severed.

40 The cam 62 is prevented from further rotation by its momentum after it has been disconnected from its actuating shaft 26 by a braking mechanism comprising a rod 184 extending parallel to the shafts 24, 26 and supported for limited longitudinal sliding movement in a hub provided on the lower arm 130 of the yoke 124. The forward end of the rod 184 is connected at 185 to one end of a lever 186 fulcrumed at 187 on the frame and having its other end in engagement with 45 a friction plug 188 received in a recess in the frame and having its forward end engaging the rear surface of the cam 62. The rod 184 is normally influenced to keep the plug 188 in braking engagement with the cam 62 by a 50 spring 190 surrounding the rearwardly projecting portion of the rod and interposed between the arm 130 and adjusting nuts 192 on the rod. The cam 62 is mounted on a bearing 194, Fig. 6, surrounding the shaft 55 26, and the spring of the several parts is

sufficient to cause the plug 188 to force the cam against a coöperating brake member 196 engaging the front face of the cam.

Means are provided for automatically initiating the movement of wire feeding mechanism at such times only as will insure the full length of the initial fastening inserted in the work according to the thickness of work upon the horn and also for automatically suspending the operation of the wire feeding mechanism at predetermined times in the cycle of operations of the machine. The illustrated mechanism comprises a lever 198 pivoted on a stud 200 in the frame and having its upper end provided with a socket 202 which receives a block 203 attached to the under side of the end of the yoke 124. The lower end of the lever 198 is pivotally connected at 204 to a horizontal link 205 which carries at its forward end a block 206 supported in the frame of the machine. This block has a vertical slot 208 through which the lower end of a rod 210 projects, the rod being attached at its upper end to an arm 211 of the wire feed lever 34. This rod 80 forms one leg of the work caliper means, the other leg of said means being secured to an arm projecting from the horn shaft 90. The opposed ends of both rods are confined in a sleeve, all as more fully shown and described in United States Letters Patent No. 908,437, granted January 5, 1909, on an application of G. A. Ambler. The lower end of the rod 210 carries an adjustable collar 216 which is adapted to pass through a portion of the slot 208 in the block 206 when the wire feed lever is in operative relation to its actuating cam 46. In the normally inoperative or suspended position of the wire feed lever, the collar 216 rests upon a 85 supporting ledge 218 formed in the block 206, as shown in Fig. 5.

90 It will be seen that as the cam 62 is connected to its actuating shaft 26 to render the machine operative to insert fastenings, which 95 connection occurs immediately after a complete cycle of operations of the machine, the movement of the yoke will simultaneously cause the block 206 to be withdrawn from under the collar 216. The wire feed lever is 100 immediately moved into operative position under the influence of the yielding means (not shown) to receive the proper wire feeding movement of the cam according to the thickness of the work upon the horn whereby the full length of the initial fastening inserted in the work is insured. When the treadle 98 is released, the action of the cam 180 to disconnect the clutch automatically moves the block 206 into position under the 105 collar 216 of the rod and thus suspends the operation of the wire feeding mechanism.

110 In order to insure a complete initial operation of the machine and to prevent a premature lowering of the horn 2 if the oper- 115

ator releases the treadle before the last fastening has been completely inserted, means are provided for locking the horn in operative position until a predetermined proper time in the cycle of operations of the machine or until a complete cycle of operations has occurred.

The means herein shown comprises a bracket 220 depending from the lower arm 130 of the yoke 124 and having pivotally mounted thereon a stud 225 and pawl 226 which is normally and yieldingly held in substantially upright position (see Fig. 2) by a spring pressed plunger 228 located in a vertical lug 229 on the bracket 220. The bell-crank lever 168, rigidly secured to the shaft 170, has a laterally projecting arm 224 the forward end of which is normally disposed in substantially the same vertical plane as the pawl 226, as shown in Fig. 7, and has a bottom face adapted to coöperate with a supporting face 230 provided on the end of the pawl 226. Upon depression of the treadle 98 to start the machine, the forward end of the arm 224 is moved upwardly during which movement it engages the pawl 226 and moves it out of the way until the end of the arm 224 is above the pawl 226 at which time the pawl, under the influence of its spring pressed plunger 228, immediately snaps under the end of the lever 224 and prevents it from dropping back into normal position, should the operator release the treadle, until the clutch has had an opportunity to move into operative relation to the cam 62. The movement of the yoke 124 into operative position through the operation of the clutch then carries the pawl 226 from under the end of the arm 224. It will thus be seen that a complete initial cycle of the machine is insured upon depression of the treadle 98 regardless of length of time the treadle is held in depressed position. Projecting into the path of the end of the arm 224 when the yoke 124 is in operative position is a flat shelf 222 formed on the side of the bracket 220. When the operator releases the treadle to stop the machine, the end of the arm 224 engages the shelf 222 which prevents the treadle from returning to its normal inoperative position. The location of this shelf is such as will allow the treadle to release sufficiently to bring the cam roll 154 of the arm 150 into operative relation to the cam 180. The treadle, however, is prevented from returning to its completely released position so that the toggle 80, 82 remains straight and the horn 2 is maintained in work clamping position until the fastening is completely inserted. As the yoke 124 is moved rearwardly and the clutch member withdrawn from engagement with the cam 62 which occurs at a predetermined time and after all operations in that cycle have been completed, the shelf 222 is moved from under the arm 224 where-

upon the treadle immediately returns to normal position and breaks the toggle 80, 82 to lower the horn and allow the work to be removed. A treadle 235 fulcrumed on the shaft 86 has its rear end 236 arranged to engage a portion of the lever 84 back of its fulcrum to lower the horn 2 beyond the point provided for by the treadle 98.

The operation of the machine may be described briefly as follows:

The parts being in the positions shown in Fig. 1, the operator places the shoe or other work upon the horn 2 and then depresses the treadle 98. As the treadle 98 is depressed, the link 92 is moved rearwardly thus straightening the toggle 80, 82 and raising the horn into work clamping position, the spring 66 being placed under tension at the same time. The depression of the treadle 98 also rocks the lever 168 clockwise about its pivot 170 and through the rod 156 moves the arm 150 about its pivot 152 into position to engage the arm 144 and release the outer end of the yoke 124. Upon the release of the outer end of the yoke 124, by the arm 144, the clutch springs 112, 114 move the plungers 109 and 111 into position in the recesses 116, 118 of the wire severing cam 62 which also draws the yoke member forwardly, the recesses in the cam 62 being so located that they only receive the plungers immediately after one complete cycle of operations of the machine has occurred. The movement of the yoke 124 forwardly into operative position causes the lever 198 to be oscillated about its pivot 200 whereby the lower end of the lever withdraws the block 206 from under the stop 216 of the depending arm of the wire feed lever 34 thus allowing the wire feed lever to move into engagement with the wire feeding cam 46. Also, as the treadle 98 is depressed, the arm 224 of the bell-crank lever 168 positions itself upon the top of the spring pressed pawl 226 so as to prevent the treadle from returning to its normal inoperative position until the clutch springs have had an opportunity to engage the plungers with the wire severing cam 62, thus insuring a complete cycle of operations of the machine whenever the machine is treadled. The movement of the yoke 124 forwardly upon movement of the clutch mechanism into clutching position then causes the spring pressed pawl 226 to be withdrawn from under the end of the arm 224 whereupon the arm drops down on to the shelf 222 on the bracket 220 providing, of course, the operator has removed his foot from the treadle. As long as the treadle 98 remains depressed, the machine will insert a fastening for each half rotation of the shaft 26. When the treadle 98 is released, the bell-crank 168 is moved in a counter clockwise direction which returns the arm 150 into position to be engaged by

the continuously rotating cam 180 on the shaft 24. The cam face 182 of this cam then engages the roll 154 on the forward end of the arm 150 and moves the yoke 124 rearwardly to withdraw the plungers 109, 111, against the tension of the springs 112, 114, out of the recesses in the wire severing cam 62. The rearward movement of the yoke 124 then causes the arm 198 to be oscillated 5 so as to move the block 206 into position for the stop 216 to seat itself upon the shoulder 218 of the block upon the next feeding movement of the wire feed lever 34. The action of the cam face 182 on the roll 154 tends to 10 move the forward end of the arm 150 to the right, Fig. 3, before acting directly to move the outer end of the yoke rearwardly and this clockwise movement of the forward end of the arm 150 is taken up by the spring 162 which is interposed between the rear end 15 of the arm 150 and the adjustable stop 160 on the rod 156. After the spring 162 has been compressed upon lateral movement of the arm 150 by the cam 182, the cam moves 20 the yoke 124 rearwardly into position where it can be held by the arm 144. After the cam 182 has imparted the full amount of throw to the yoke, the spring 162 immediately overcomes the tendency of the cam to keep the 25 forward end of the arm 150 forced to the right (Fig. 3) and immediately moves the end of the arm 144 to the left (Fig. 3) a distance sufficient to position it out of the way of the cam to prevent any further engagement with the cam. In order that the 30 horn 2 shall not be released before the complete insertion of the final fastening in the work, the lever 224 is held upon the shelf 222 of the bracket until the yoke 124 has 35 been returned to its normal inoperative position, which movement carries the shelf from under the end of the arm 224 and allows the arm 224 to drop the remaining distance, this distance being sufficient to use up 40 the lost motion between the link 92 and its connection with the treadle so as to permit the toggle 80, 82 to be broken. Further rotation of the wire severing cam 62 by its momentum is prevented by the brake member 188 which is pressed into engagement 45 with the rear face of the wire severing cam 62 by an arm 102 one end of which engages the brake member 188 and the other end of which is yieldingly connected through a 50 spring 190 to the arm 130 of the yoke, the rearward movement of the yoke causing the arm 102 to fulcrum about its pivot and engage the brake member 188.

Having described my invention, I claim 55 as new and desire to secure by Letters Patent of the United States:

1. A machine for inserting fastenings comprising a continuously rotating wire carrying spindle, lateral shafts continuously driven from said spindle, wire feeding

means operated from one of said shafts, means for initiating the operation of said wire feeding means, and means operated by the other of said shafts for suspending the operation of said wire feeding means. 70

2. A machine for inserting fastenings comprising a continuously rotating wire carrying spindle, lateral shafts continuously driven from said spindle, wire feeding means operated from one of said shafts, 75 means for initiating the operation of said wire feeding means, and means operated by the other of said shafts in timed relation with the first said shaft for controlling the operation of said wire feeding means. 80

3. A machine for inserting fastenings comprising a continuously rotating wire carrying spindle, lateral shafts continuously driven from said spindle, wire feeding means operated from one of said shafts, 85 automatic means for initiating the operation of said wire feeding means, and means operated by the other of said shafts for suspending the operation of said wire feeding means. 90

4. A machine for inserting fastenings comprising a continuously rotating wire carrying spindle, lateral shafts continuously driven from said spindle, wire feeding means, means operated automatically by 95 one of said shafts to render said wire feeding means operative, and means operated automatically by the other of said shafts to suspend the operation of said wire feeding means. 100

5. A machine for inserting fastenings comprising a continuously rotating wire carrying spindle, lateral shafts continuously driven from said spindle, wire feeding means, connections between said wire 105 feeding means and one of said shafts for initiating the operation of the wire feeding means, and means operated from the other of said shafts for rendering said connections inoperative to suspend the operation of the 110 wire feeding means.

6. A machine for inserting fastenings comprising a continuously rotating wire carrying spindle, lateral shafts continuously driven from said spindle, wire feeding means, means operated by one of said shafts to render said wire feeding means operative, and means operated by the other of said shafts to suspend the operation of 115 said wire feeding means. 120

7. In a machine for inserting fastenings, fastening inserting means, a power driven cam shaft, means for operatively connecting said fastening inserting means to the cam shaft, a countershaft, and means operated by said countershaft to disconnect the fastening inserting means from the cam shaft. 125

8. A machine for inserting fastenings comprising a continuously rotating wire carrying spindle, lateral shafts continuously 130

driven from said spindle, wire feeding means, means operated from one of said shafts to render the wire feeding means operative, and means operated by the other 5 of said shafts for suspending the operation of the wire feeding means at predetermined times only in the cycle of operations of the machine.

9. A machine for inserting fastenings 10 comprising wire feeding means and operating mechanism therefor, a continuously driven shaft independent of said operating mechanism, and connections between said wire feeding means and said shaft constructed and arranged to operate automatically 15 to suspend the operation of said wire feeding means at predetermined times only in the cycle of operations of the machine.

10. A machine for inserting fastenings 20 comprising a continuously rotating wire carrying spindle, lateral shafts continuously driven from said spindle, wire feeding means, means operated automatically by one of said shafts to render said wire feeding means operative at predetermined times in the cycle of operations of the machine, and means operated by the other of said shafts to suspend the operation of said wire feeding means.

30 11. A machine for inserting fastenings comprising wire feeding means and operating mechanism therefor, a continuously driven shaft independent of said operating mechanism, connections between said wire feeding means and said shaft constructed and arranged to suspend automatically the operation of said wire feeding means at predetermined times in the cycle of operations of the machine, and manual means for controlling the operation of said automatic means.

12. A machine for inserting fastenings 45 comprising a continuously rotating wire carrying spindle, lateral shafts continuously driven from said spindle, wire feeding means, means tending normally to connect said wire feeding means with one of said shafts at predetermined times in the cycle of operations, means operated by the other 50 of said shafts to suspend the operation of said wire feeding means at predetermined times in the cycle of operations of the machine, and manually operated means for controlling the operation of both the wire feed connecting means and the wire feed suspending means.

13. A machine for inserting fastenings 60 comprising wire feeding means, a continuously driven shaft normally connected operatively to said wire feeding means, wire severing means normally disconnected from said shaft, and a clutch device constructed and arranged to establish an operative connection between said wire severing means and 65 said operating shaft.

14. In a machine for inserting fastenings, a continuously rotating wire carrying spindle, lateral shafts continuously driven from said spindle, wire feeding and wire severing means operated from one of said shafts, 70 means for connecting said wire feeding and said wire severing means to their said operating shaft, and means operated by the other of said shafts to disconnect said wire feeding and wire severing means from their 75 operating shaft.

15. In a machine for inserting fastenings, a continuously rotating wire carrying spindle, lateral shafts continuously driven from said spindle, wire feeding and wire 80 severing means operated from one of said shafts, means for connecting said wire feeding and said wire severing means to their said operating shaft, and means operated by the other of said shafts to disconnect said 85 wire feeding and wire severing means from their operating shaft at predetermined times in the cycle of operations of the machine.

16. In a machine for inserting fastenings, a continuously rotating wire carrying 90 spindle, lateral shafts continuously driven from said spindle, wire feeding and wire severing means operated from one of said shafts, means for simultaneously connecting said wire feeding and said wire 95 severing means to their said operating shaft, and positive means operated by the other of said shafts to disconnect said wire feeding and said wire severing means from their operating shaft at predetermined times in 100 the cycle of operations of the machine.

17. In a machine for inserting fastenings, wire feeding and wire severing means, a continuously rotating shaft carrying parts of 105 said wire feeding and wire severing means from which said means are operated, a clutch upon said shaft for connecting said shaft with said wire severing means, and connections between said clutch and said wire feeding means for connecting said wire feeding 110 means with said shaft upon operative movement of the clutch.

18. In a machine for inserting fastenings, wire feeding and wire severing means, a continuously rotating shaft carrying parts of 115 said wire feeding and wire severing means from which said means are operated, and a clutch upon said shaft constructed and arranged to connect said shaft to said wire severing means and simultaneously to render 120 said wire feeding means operative.

19. In a machine for inserting fastenings, wire feeding means, continuously rotating shafts from one of which said means are operated, a clutch upon said last named shaft 125 constructed and arranged to render said wire feeding means operative, and means operated from the other of said shafts for disconnecting the clutch.

20. In a machine for inserting fastenings, 130

wire severing means, continuously rotating shafts from one of which said means are operated, a clutch upon said last named shaft constructed and arranged to connect said shaft to said wire severing means, and means operated from the other of said shafts for disconnecting the clutch from its shaft.

21. In a machine for inserting fastenings, a continuously rotating wire carrying 10 spindle, wire severing means, horn releasing means, a continuously rotating shaft, said shaft being driven from said spindle, an actuator for said wire severing means and said horn releasing means loosely mounted on said shaft, and a clutch upon said shaft by which said shaft may be operatively connected to said actuator and clutch controlling means.

22. In a machine for inserting fastenings, 20 wire severing means, horn releasing means, continuously rotating shafts from one of which said means are operated, a clutch device upon one of said shafts by which said shaft may be operatively connected to said wire severing and horn releasing means, and means operated from the other shaft for disconnecting said wire severing and said horn releasing means from its operating shaft.

23. In a machine for inserting fastenings, 30 wire severing means, a continuously rotating shaft, a cam on said shaft for operating said wire severing means, and a normally inoperative clutch constructed and arranged to connect said cam to said shaft for operating said wire severing means.

24. A machine for inserting fastenings comprising a continuously rotating wire carrying spindle, parallel shafts continuously driven from said spindle, wire feeding means 40 operated from a cam on one of said shafts and normally disconnected therefrom, wire severing means operated from a cam on one of said shafts, and a clutch between said wire severing cam and its shaft and operating to connect said wire severing cam to its shaft and simultaneously to connect said wire feeding means to its cam.

25. In a machine for inserting fastenings, a continuously rotating wire carrying 50 spindle, lateral shafts continuously driven from said spindle, wire feeding means operated from a cam on one of said shafts and normally disconnected therefrom, wire severing means operated by a cam on one of said shafts, and a clutch located between said wire severing cam and its shaft and operating automatically at predetermined times in the cycle of operations of the machine to connect said wire severing cam to its shaft and simultaneously to connect said wire feeding means to its cam.

26. In a machine for inserting fastenings comprising a continuously rotating wire carrying spindle, lateral shafts continuously 60 driven from said spindle, wire feeding

means operated from a cam on one of said shafts and normally disconnected therefrom, wire severing means operated by a cam on one of said shafts and a clutch located between said wire severing cam and its shaft 70 and operating automatically at predetermined times in the cycle of operations of the machine to connect said wire severing cam to its shaft and simultaneously to connect said wire feeding means to its cam, and manual means for controlling said clutch.

27. In a machine for inserting fastenings, a continuously rotating wire carrying spindle, lateral shafts continuously driven from said spindle, wire feeding means operated from a cam on one of said shafts, a clutch on said cam shaft for rendering said wire feeding means operative, and a cam upon the other of said shafts constructed and arranged to render said clutch inoperative at 80 predetermined times in the cycle of operations of the machine.

28. In a machine for inserting fastenings, a continuously rotating wire carrying spindle, lateral shafts continuously driven from 90 said spindle, wire feeding means operated from a cam on one of said shafts and normally disconnected therefrom, wire severing means operated by a cam on one of said shafts, a clutch located between said wire severing cam and its shaft and operating to connect said wire severing cam to its shaft and having connections to said wire feeding means to connect the wire feeding means to its cam, and a cam upon the other of said shafts constructed and arranged to render said clutch inoperative to suspend the operation of the wire feeding and wire severing means at predetermined times in the cycle 100 of operations of the machine.

29. In a machine for inserting fastenings, wire feeding means and wire severing means, a continuously rotated shaft carrying means for operating the wire feeding means and means for operating the wire severing means, 110 means for supporting the wire feeding means for movement into and out of operative relation to its operating means, and a clutch upon said shaft constructed and arranged to connect said shaft to said wire severing means and simultaneously to permit movement of the wire feeding means into operative relation to its operating means.

30. A machine for inserting fastenings 120 comprising a shaft, means for rotating said shaft, wire guiding means, means comprising an operating member rigidly connected to the shaft for feeding the wire through said guiding means, means comprising an operating member loosely connected to the shaft for severing the wire to form fastenings, and means for locking the operating member for the wire severing means in operative relation to said shaft. 130

31. A machine for inserting fastenings comprising a shaft, means for rotating said shaft, a rotary actuator fixed to said shaft, feeding means operated by said actuator, a rotary actuator mounted loosely on said shaft, horn-depressing mechanism operated by said actuator, and means for securing the last-named actuator in fixed position on said shaft.
- 10 32. A machine for inserting fastenings comprising a shaft, means for rotating said shaft, wire feeding means, operating mechanism therefor normally connected operatively to the shaft, wire severing means, and operating mechanism therefor normally in inoperative relation to the shaft.
- 15 33. A machine for inserting fastenings comprising a shaft, means for rotating said shaft, wire feeding means, operating mechanism therefor comprising a cam normally connected operatively to the shaft, wire severing means, and cam mechanism for operating said wire severing means normally in inoperative relation to said shaft.
- 20 34. A machine for inserting fastenings comprising a shaft, means for rotating said shaft, wire feeding means, operating mechanism therefor normally connected operatively to the shaft, wire severing means, operating mechanism therefor normally in inoperative relation to the shaft, means for locking the operating mechanism for the wire severing means in operative relation to the shaft, and means connected with said
- 25 35. In a machine for inserting fastenings, in combination, wire severing means, means for rendering said severing means operative including a movable member, mechanism carried by said movable member for releasing the movable member to operative position, manually controlled means for operating said mechanism, and a part carried by said movable member for maintaining said manually controlled means in operative position, said part being moved out of engagement with said manually controlled means upon movement of said movable member to operative position, whereby the operation of the severing means is insured upon operation of the manually controlled means.
- 30 36. In a machine for inserting fastenings, in combination, wire severing means, means for rendering said severing means operative including a movable member, mechanism for releasing the movable member to operative position, manually controlled means for operating said mechanism, and a part fixed to said movable member for maintaining said manually controlled means in operative position, said part being moved out of engagement with said manually controlled means upon movement of said movable member to
- 31 operative position, whereby the operation of the severing means is insured upon operation of the manually controlled means.
32. In a machine for inserting fastenings, in combination, fastening inserting mechanism, power-driven mechanism operated in timed relation therewith for rendering said fastening inserting mechanism inoperative at a predetermined point in the cycle of operation of the machine, manually controlled means which upon one movement renders said fastening inserting mechanism operative and upon another movement causes said power-driven mechanism to become effectively operative, a work support, and means constructed and arranged to maintain the work support in working-clamping position subsequently to the last-mentioned movement of the manually controlled means and until the fastening inserting mechanism is rendered inoperative.
33. In a machine for inserting fastenings, in combination, wire severing means, an actuator therefor, mechanism operated in timed relation with said actuator for rendering said actuator inoperative after the severance of a length of wire by the wire severing means, means for rendering said actuator operative and for causing said mechanism to become effectively operative, a work support, and devices constructed and arranged to maintain the work support in work clamping position subsequently to the mechanism being rendered operative and until the actuator is rendered inoperative.
34. In a machine for inserting fastenings, in combination, fastening inserting mechanism, power-driven mechanism operated in timed relation therewith for rendering said fastening inserting mechanism inoperative at a predetermined point in the cycle of operation of the machine, means for rendering said fastening inserting mechanism operative and for causing said power-driven mechanism to become effectively operative, a work support, and devices comprising a lost motion connection between said means and the work support constructed and arranged to maintain the work support in work clamping position subsequently to the power-driven mechanism being rendered operative and until the fastening inserting mechanism is rendered inoperative.
35. In a machine for inserting fastenings, in combination, fastening inserting mechanism, power-driven mechanism operated in timed relation therewith for rendering said fastening inserting mechanism inoperative at a predetermined point in the cycle of operation of the machine, means for rendering said fastening inserting mechanism operative and for causing said power-driven mechanism to become effectively operative, a work support, and connections between said means and said work support for mov-

ing the work support to work-clamping position upon movement of said means to render the fastening inserting mechanism operative, said connections being constructed and arranged to lower said work support when the fastening inserting mechanism is rendered inoperative.

41. In a machine for inserting fastenings, in combination, fastening inserting mechanism, power-driven mechanism operated in timed relation therewith for rendering said fastening inserting mechanism inoperative at a predetermined point in the cycle of operation of the machine, a movable clutch member, manually operated means for controlling the movement of the clutch member into position to make the fastening inserting mechanism operative, co-acting parts connected to the clutch member and manually operated means for insuring the movement of the clutch member to operative position upon actuation of the said means, an instrumentality connected to said member for limiting the movement of said means toward inoperative position, means for rendering said power-driven mechanism effectively operative upon movement of said means into engagement with said instrumentality, a work support, and connections between said means and the work support constructed and arranged to permit the horn to remain in work-clamping position on movement of said means to engage with said instrumentality and to lower the work-support upon actuation of said clutch member by said power-driven mechanism.

42. In a machine for inserting fastenings, in combination, wire severing means, mechanism for rendering said wire severing means operative, manually controlled means for operating said mechanism, a part connected with said mechanism for maintaining the manually controlled means in operative position after it is moved to said position, an element on said mechanism lying below and to one side of said part, a work support, work support operating means, and a loose connection between said manually controlled means and the work support operating means, the construction and arrangement being such that movement of the mechanism to operative position will cause the part to move out of operative relation to the manually controlled means to permit the return of said means toward inoperative position whereby said means comes into operative relation to said element, the loose connection between the manually controlled means and the work support operating means permitting lost motion whereby movement of the manually controlled means into operative engagement with said element does not affect the position of the work support.

43. In a machine of the class described,

fastening inserting mechanism, clutch mechanism constructed and arranged when rendered operative to initiate the operation of the fastening inserting mechanism, and when rendered inoperative to suspend the operation of the fastening inserting mechanism, means for rendering said clutch mechanism inoperative at a predetermined time in the cycle of operations of the machine, controlling means for said clutch mechanism operable upon one movement to render said clutch mechanism operative and upon another movement to connect said clutch mechanism operatively with the means for rendering the clutch mechanism inoperative and constructed and arranged to have a further movement after the clutch mechanism has been rendered inoperative, a work support movable from work receiving to work presenting position, and connections between said controlling means and the work support constructed and arranged to move said work support to work presenting position upon movement of said controlling means to render said clutch mechanism operative, to permit movement of said controlling means to connect said clutch mechanism operatively with the means for rendering the clutch inoperative without affecting the work support, and to move the work support from work presenting to work receiving position upon movement of the controlling means after the clutch mechanism has been rendered inoperative.

44. In a machine of the class described, fastening inserting mechanism, a clutch member constructed and arranged when rendered operative to initiate the operation of the fastening inserting mechanism, and when rendered inoperative to suspend the operation of the fastening inserting mechanism, means for rendering the clutch member inoperative at a predetermined time in the cycle of operations of the machine, a work support movable from a work receiving to a work presenting position, controlling means for said clutch member and said work support constructed and arranged upon movement of said controlling means in one direction to move the work support from work receiving to work presenting position and to render said clutch member operative, means operated by another movement of the controlling means to connect the clutch member operatively with the means for rendering the clutch member inoperative, a loose connection between said controlling means and said work support constructed and arranged to permit said last-mentioned movement of the controlling means without moving the work support and to move the work support from work presenting to work receiving position upon further movement of said controlling means in the direction of said last-mentioned movement, and means

connected to said clutch member constructed and arranged to preclude such further movement of the controlling means previous to the clutch member being rendered inoperative and to permit such movement of the controlling means upon the clutch member being rendered inoperative whereby the work support is moved to work receiving position when the operation of the fastening 5 inserting mechanism is suspended.

45. In a machine of the class described, wire feeding means, a movable member for controlling the operation of said wire feeding means, yielding means for moving said 10 controlling member in a direction to render said wire feeding means operative, a latch for maintaining said movable member in inoperative position in opposition to the action of said yielding means, manually operated 15 means for releasing said latch to render said wire feeding means operative, and means op-

erated in timed relation to said wire feeding means for moving said member to inoperative position under the control of said latch. 25

46. In a machine of the class described, wire feeding means, a movable member for controlling the operation of said wire feeding means, a latch for maintaining said member in a position to render said wire feeding means inoperative, manually controlled means for releasing said latch to permit movement of said member to a position to render said wire feeding means operative, and means constructed and arranged to permit movement of said member to such position at a predetermined time only in the cycle of operations of the machine. 30 35

In testimony whereof I have signed my name to this specification.

LOUIS A. CASGRAIN.

Copies of this patent may be obtained for five cents each, by addressing the "Commissioner of Patents, Washington, D. C."
